UNITED STATES PATENT OFFICE

EDWARD L. MONNOT, OF CANTON, OHIO, ASSIGNOR TO THE HARVARD COMPANY, OF CANTON, OHIO, A CORPORATION OF OHIO

COMBINED HEATER AND ILLUMINATOR

Application filed September 10, 1929. Serial No. 391,608.

My invention relates to combined heaters and illuminators for use on a dental unit or the like for heating spray bottles, water glasses, and the like, and for illuminating 5 X-ray prints.

The desired characteristics of a dental appliance include maximum adaptability for the intended use, convenience of arrangement, and economy in the space occupied by 10 the appliance.

The usual dental unit may be equipped with a heater for heating spray bottles, water glasses, and the like, by means of an electric lamp enclosed in a housing having 15 apertures formed therein for receiving the spray bottles, glasses and the like, and a rheostat for controlling the heat dissipated by the lamp.

The usual dental unit may also be equipped 20 with a separate X-ray print illuminator, and it is a characteristic of X-ray prints that the same degree of illumination is not satisfactory for properly viewing different prints.

On the other hand when a lamp bulb is 25 used as a heater element in combination with a rheostat located adjacent the bulb, such as a socket rheostat, the heat dissipated by the rheostat, when the rheostat has been operated to reduce the illumination of the lamp, plus 30 the heat dissipated by the dimmed lamp may be substantially equal to the heat dissipated by the lamp at maximum illumination.

The objects of the present improvements include the provision of a combined heater 35 and illuminator in which a lamp bulb is utilized both as a heating and illuminating element, and is mounted within a novel housing arranged for receiving the bottles, glasses, and the like for being heated; and 40 having a suitably positioned translucent sheet of material such as opal glass, through which the varying degrees of light may pass for satisfactorily illuminating different X-ray prints.

45 Further objects of the improvements include the provision of an improved structure and arrangement for the light and associated rheostat, whereby heat from the rheostat is dissipated and not introduced into the heating and illuminating chamber of the housing.

These and other objects are attained by the present improvements, as will be set forth hereinafter in greater detail and claimed.

A preferred embodiment of the improvements is illustrated in the accompanying 55 drawings forming part hereof, in which

Figure 1 is a fragmentary elevation view of one embodiment of the improved combined heater and illuminator, detached from its usual support on a dental unit;

Fig. 2, a top plan view thereof;

Fig. 3, a transverse sectional view thereof as on line 3—3, Figs. 1 and 2;

Fig. 4, another transverse sectional view thereof as on line 4—4, Figs. 1 and 2;

Fig. 5, a view similar to Fig. 1 with the upper section of the housing removed; and

Fig. 6, a view similar to Fig. 2 with the upper section of the housing removed.

Similar numerals refer to similar parts 70 throughout the several views.

The improved combined heater and illuminator indicated generally at 10 is illustrated in the drawings detached from its usual support on the standard of a dental unit or the 75 like.

The combined heater and illuminator 10 includes a housing comprising a base section 11 and a cover section 12.

The base section 11 preferably includes an 80 upwardly opening channel member 13 secured at one side to a supporting plate 14 which is adapted to be secured to the standard or the like of a dental unit.

One end of the channel member 13 terminates in an upwardly extending tongue 15 for fitting within one end 16 of the bottom of the cover section 12.

The other end of the base section includes 90 an upwardly extending end cover and rheostat knob mounting plate 17, which fits over the end of adjacent inverted U wall 18 of the cover section 12.

Adjacent the end plate 17, the channel member 13 carries a clamp 19 which removably mounts a socket rheostat 20.

A preferably long cylindric electric lamp 21 is mounted in the socket rheostat 20.

Adjacent the lamp receiving end of the socket rheostat, a transversely extending 100

baffle partition 22 is mounted on the channel member 13, and the lamp 21 extends through an aperture 23 in the baffle partition, the size of the aperture being just sufficient to permit clearance of the lamp, and the baffle member being adapted to prevent a flow of the heat dissipated from the socket rheostat into the space surrounding the lamp.

The end cover and rheostat knob mounting plate 17 has journalled therein the shaft 24 of a rheostat knob 25, the knob being located on the outside of the plate 17, and the shaft extending through the plate and carrying on its inner end a radially extending arm 26 from the outer end of which a rheostat actuating rod 27 extends longitudinally over the clamp 19 to the socket rheostat and passes through a loop 28 on the rotatable resistance varying sleeve 29 of the socket rheostat, whereby rotation of the knob 25 rotates the sleeve 29 and increases or decreases the resistance in series with the lamp in a well known manner.

The inverted U wall 18 of the cover section 25 extends, when in position, from the end plate 17 to a junction with upwardly extending well walls 30 forming an interior illuminating and heating chamber 31.

The baffle partition 22 extends across the inner end 32 of the inverted U wall 18, and openings 33 are formed in one side of the U wall 18 for permitting dissipation of heat from the rheostat socket 29 through the openings into the atmosphere.

35 The well walls 30 have an illuminating opening 34 formed at the outside or front 35 thereof, and preferably include oppositely opening parallel grooves 36 and 36', the plane of which slopes downwardly from the upper 40 end of the well walls, and in which a sheet or plate 37 of translucent glass or the like is mounted in the angled position best illustrated in Fig. 3, whereby X-ray prints may be rested on the top outer surface of the 45 glass plate and may be illuminated to the proper intensity by manipulation of the rheostat knob 25.

The upper end of the well walls 30 are connected by a transverse normally horizontal web 38 in which are formed a plurality of openings 39 and 39', the end openings 39 each being adapted for receiving a spray bottle 40, and the central opening 39' being adapted for receiving a water glass 41, the 55 spray bottle and the glass each extending a substantial distance into the heating chamber 31 for being heated to the desired degree therein by suitable adjustment of the rheostat knob.

60 A screw 42 may extend through a suitable aperture in the lower end of the cover section, and screw into the base tongue 15 for securing the cover section on the base.

Accordingly, a compact combined heater 65 and illuminator is provided by which a single

electric lamp is utilized for providing varying degrees of heat, and for providing varying degrees of illumination for reading X-ray prints and the like, and the structure and arrangement of the appliance is such that when the lamp is illuminated at less than maximum intensity, the heat dissipated by the rheostat is prevented from entering the heating and illuminating chamber by the baffle partition, and passes into the atmosphere through the openings 33 of the cover section.

I claim:

1. A combined heater and illuminator including walls forming a chamber, an electric heater lamp within the chamber, one of the walls having openings formed therein for receiving articles to be heated in the chamber, another of the walls having an illuminating opening formed therein, a rheostat in the chamber for variably controlling the lamp, and a baffle wall between the rheostat and the lamp.

2. A combined heater and illuminator including walls forming a chamber, an electric heater lamp within the chamber, one of the walls having openings formed therein for receiving articles to be heated in the chamber, another of the walls having an illuminating opening formed therein, a pane of translucent material inclined to the vertical and closing the illuminating opening, a rheostat in the chamber for variably controlling the lamp, and a baffle wall between the rheostat and the lamp.

3. A combined heater and illuminator including walls forming a chamber, a heater lamp within the chamber, one of the walls having openings formed therein for receiving articles to be heated in the chamber, another of the walls having an illuminating opening formed therein, and means within the chamber for varying the intensity of the heater lamp.

4. A combined heater and illuminator including walls forming a chamber, a heater lamp within the chamber, one of the walls having openings formed therein for receiving articles to be heated in the chamber, another of the walls having an illuminating opening formed therein, a pane of translucent material inclined to the vertical and closing the illuminating opening, and means within the chamber for varying the intensity of the heater lamp.

5. A combined heater and illuminator including walls forming a chamber, an electric heater lamp within the chamber, one of the walls having openings formed therein for receiving articles to be heated in the chamber, another of the walls having an illuminating opening formed therein, a rheostat in the chamber for variably controlling the lamp, a baffle wall between the rheostat and the lamp, and means for dissipating the heat

from the rheostat directly into the atmosphere.

6. A combined heater and illuminator including walls forming a chamber, an electric heater lamp within the chamber, one of the walls having openings formed therein for receiving articles to be heated in the chamber, another of the walls having an illuminating opening formed therein, a rheostat in the chamber for variably controlling the lamp, a baffle wall between the rheostat and the lamp, and openings formed in the chamber walls adjacent the rheostat for dissipating the heat from the rheostat into the atmosphere.

15 7. A combined heater and illuminator including walls forming a heating and illuminating chamber and a variable control chamber adjacent thereto, a heater lamp in the 20 heating and illuminating chamber and openings formed in the walls of the chamber for receiving articles to be heated in the chamber, and a rheostat in the variable control chamber for variably controlling the lamp.

25 8. A combined heater and illuminator including walls forming a heating and illuminating chamber and a variable control chamber adjacent thereto, a heater lamp in the heating and illuminating chamber and openings formed in the walls of the chamber for receiving articles to be heated in the chamber, a rheostat in the variable control chamber for variably controlling the lamp, and means for dissipating the heat from the rheostat directly into the atmosphere.

30 9. A combined heater and illuminator including walls forming a heating and illuminating chamber and a variable control chamber adjacent thereto, a heater lamp in the 35 heating and illuminating chamber and openings formed in the walls of the chamber for receiving articles to be heated in the chamber, a rheostat in the variable control chamber for variably controlling the lamp, and openings formed in the walls of the variable control chamber for dissipating the heat from the rheostat into the atmosphere.

In testimony that I claim the above, I have hereunto subscribed my name.

EDWARD L. MONNOT.
